UNITED STATES PATENT OFFICE.

WILLIAM B. GOULD, OF NEW YORK, N. Y.

DESIGN FOR A STAIR-ROD FASTENING.

Specification forming part of Design No. 5,203, dated August 15, 1871.

To all whom it may concern:

Be it known that I, WILLIAM B. GOULD, of the city of New York, in the county and State of New York, have invented a new and original Design for a Stair-Rod Fastening; and I do hereby declare that the following is a full, clear, and exact description thereof, which will enable others skilled in the art to make and use the same, reference being had to the accompanying drawing forming part of this specification.

The drawing represents a perspective view of my new form of stair-rod fastening.

This invention relates to a new form of stair-rod fastening independent of the operating mechanism of the same.

The body of the stair-rod fastening is in form of a barrel, ornamented in a suitable manner,

and provided with a conical projecting end, as shown. From the barrel project two ears, *a* and *b*, perforated to receive screws, whereby the barrel is secured to the stairs. These ears stand at right angles to each other.

I do not desire to restrict myself to the particular ornamentation of the surface of the barrel and ears, as shown in the drawing; but

What I claim is—

The design for a stair-rod fastening, consisting of a barrel, *A*, provided with a conical end and perforated ears, as shown.

WM. B. GOULD.
